UNITED STATES PATENT OFFICE

ROY T. AXE, OF SYRACUSE, NEW YORK, ASSIGNOR TO THE O. M. EDWARDS COMPANY, INC., OF SYRACUSE, NEW YORK, A CORPORATION OF NEW YORK

WINDOW-GUIDE CONSTRUCTION FOR REMOVABLE SASHES

Application filed May 23, 1928. Serial No. 280,045.

This invention relates to window and window sash constructions, particularly window guide constructions by which the sash is non-rattling and weather tight, and also by 5 which the sash is readily removable, and it has for its object a particularly simple, economical and compact construction of a sash guide.

The invention consists in the novel features 10 and in the combinations and constructions hereinafter set forth and claimed.

In describing this invention, reference is had to the accompanying drawings in which like characters designate corresponding 15 parts in all the views.

Figure 1 is a transverse sectional view through one side of a window frame and the sash guide, the sashes being also shown and the construction shown being adapted 20 for a double window.

Figure 2 is a fragmentary elevation, partly in section, of the sash guide with the removable strip of the guide omitted.

Figure 3 is a fragmentary isometric view 25 of the removable strip.

Figure 4 is an edge view thereof.

Figure 5 is a sectional view of a modified form of said guide.

This window construction comprises a 30 window frame element and a sash element, one of said elements being a channel for receiving the other element, one wall of the channel being detachable and having a lever movement relatively to the sash and spring 35 means acting on the strip for moving it on its fulcrum toward the sash and thus making the structure weather tight and hold the sash from rattling.

In the illustrated embodiment of my in- 40 vention the frame is formed with a channel for receiving the sash.

1 designates the guide which has a wall 2 forming one side of the channel which receives the sash 3 or the stile thereof.

45 4 designates the strip forming the other wall of the channel, this strip having an angularly extending arm 5 at its base or outer edge. The strip 4 and arm 5 form an angle or bell crank lever which fulcrums near its angle.

The arm 5 in the illustrated embodiment of my invention extends transversely of the guide or the edge of the sash and springs to be presently described act on the ends of the arms to rock on the angle lever formation 55 and press the strip against the sash and press the sash toward the wall 2.

The strip 4 in the illustrated embodiment fulcrums at 6 on the frame 7 to which the 60 guide is secured.

The guide here shown is preferably formed up of sheet metal and includes a hollow stop portion 8 of which the wall 2 forms a part and the bottom portion 9 and the arm 5 extending through a passage in the portion 65 into the stop 8.

Usually, the bottom portion 9 is formed with an outwardly extending angular flange 10 at its edge remote from the flange 2, and the edge of the flange bears against the frame 7, 70 and also the flange 10 is formed with a passage 11 for receiving the arm 5.

Each strip 4 is provided with a plurality of these arms 5 and hence the flange 10 is provided with a corresponding number of passages or slots 11. Also the bottom portion 9 is formed with offsets or indentations 12 which rest on the frame 7 and the guide is secured to the frame by screws 13 extending through the offsets and into the frame. The 80 offsets 12 form a rack with which a sash lock or holder, not shown, coacts.

The arms 5 thus extend under the bottom portion 9 into the hollow stop 8. Although the angle lever composed of the strip 4 and the arms 5 fulcrums on the frame 7, nevertheless, as shown in Figure 5, it may fulcrum on a lip 14 provided on the flange 10.

The spring means for pressing the strip 4 against the sash is preferably associated with 90 the guide and is self-contained therewith and is preferably located in the hollow stop 8. This spring means, as here shown, comprises leaf springs 15 one for each arm 5, the springs being anchored at one end at 16 to the top wall of the hollow stop and pressing at its other end against the corresponding arm 5.

The strip 4 is detachably held in position by the arms 5 interlocking with the guide 1 or with the springs 15 or with both, and 100

as here illustrated, the arms 5 are detachably interlocked with both the guide 1 and the springs 15. It is interlocked with the guide by successive inward and endwise movements of the strip and with the springs at the same by the endwise movement.

As here illustrated, the arms are provided with slots 16^a at their junctures with the strip 4 so that when the strip is pressed against the sash, these slots 16 move in line with the portions 17 of the flange 10 at one end of each slot 11 and when the strip is moved endwise, the slot 16 interlocks with said portion 17. Also the arms are provided with slots or de-

10 pressions 18 at their ends arranged to come into register with projections or deflections 19 at the free ends of the springs 15 so that upon the endwise movement of the strip to interlock the slots 16 with the portion 17 of flange 10, the projections 19 snap into the slots 18 and hold the strip from return end-

15 wise movement.

20 The extreme ends of the springs are deflected upwardly at 20 to avoid liability of the ends of the spring catching on the arms 5.

The window here shown is of double construction, although the features just described are equally adaptable to a single construction, as shown in Figure 5.

25 In the double construction, the stop 8 forms the outer stop of one sash and the inner stop for the other, and the springs 15 are common to the arms 5 of the strips 4 on the inner side of one sash and the outer side of the other sash.

30 In operation, the strips 4 are pressed against the sash to hold it from rattling and to form a weather tight structure, the springs acting through the bell crank lever composed of the strips 4 and the arms 5.

35 To remove the sash, it is necessary to force the strips 4 downwardly applying enough force to cause the projections 19 on the springs to ride up the sides of the slots 18 onto the flat part of the arms and then withdraw the strip rectilinearly outwardly. This endwise movement disengages the slots 16 from the portion 17 of the flange 10.

40 When this strip is removed, the sash can be moved laterally out of the guide. The strip 4 is replaced by the reverse of this operation.

Owing to the bell crank formation of the strips 4 and arms 5, the arrangement of the 45 arms transversely of the guide, and the association of the springs 15 with the guide, the structure is particularly simple, compact and self-contained and the pressure exerted by the strip 4 is positive at all times.

50 What I claim is:

1. A window construction comprising a frame element and a sash element, one of said elements being provided with a channel for receiving the other element, one side wall of the channel being movable toward and from

the other element and formed with an angular arm rigid therewith at its base and extending at an angle thereto whereby said wall and the angular arm form an angle lever fulcrumed near the angle of the lever formation, and means coacting with the arm to move said lever on its fulcrum.

2. A window construction comprising a frame element and a sash element, one of said elements being provided with a channel for receiving the other element, one side wall of the channel being movable toward and from the other element and formed with an angular arm rigid therewith and extending in a direction crosswise of said side wall and of the channel, whereby said wall and the arm form an angle lever fulcrumed near the angle of the wall and the arm and means acting on the arm to move the angle lever on its fulcrum and move said wall toward said other element.

3. A window construction comprising a frame element and a sash element, one of said elements being provided with a channel for receiving the other element, one side wall of the channel being movable toward and from said other element and formed with an angular arm rigid therewith at one edge thereof and extending at an angle to said side wall whereby said wall and the arm form an angle lever fulcrumed near its angle and spring means coacting with the arm to move the lever on its fulcrum and move said wall toward said other element.

4. A window construction comprising a frame element and a sash element, one of said elements being provided with a channel for receiving the other element, one side wall of the channel being movable toward and from said other element and formed with an angular arm rigid therewith at one edge thereof, the arm extending in a direction crosswise of said side wall and of the channel, said wall and the angular arm forming an angle lever fulcrumed near its angle, and spring means coacting with said arm to move the lever on its fulcrum and press said wall against said other element.

5. A window construction comprising a frame element and a sash element, one of said elements being provided with a channel for receiving the other element, one side wall of the channel being movable toward and from said other element and formed with an angular arm rigid therewith at one edge thereof and extending at an angle to said side wall, said wall and the arm forming an angle lever fulcrumed near its angle, and spring means carried by the guide and acting on said arm to move the angle lever on its fulcrum and press said wall against said other element.

6. A window construction comprising a frame element and a sash element, one of said elements being provided with a channel for receiving the other element and comprising a body formed with one side and the bottom

of the channel and a strip forming the other side of the channel, the strip having an angular arm rigid therewith at its base and extending in a direction crosswise of the strip and of the channel, said arm having means for detachably interlocking with the body whereby the strip is removable.

7. A window construction comprising a frame provided with a sash guide in the form of a channel for receiving the sash, the guide comprising a body having a flange forming one side wall of the channel and a portion forming the bottom of the channel, the bottom portion being provided with an outwardly extending flange at its edge remote from the former flange spacing the bottom portion of the body away from the frame, the second mentioned flange having a passage therethrough, the guide also comprising a strip forming the other wall of the channel, the strip having an arm at its base extending through the passage under the bottom of the body, said arm having means for detachably interlocking with the second mentioned flange.

8. A window construction comprising a frame provided with a sash guide in the form of a channel for receiving the sash, the guide comprising a body having a flange forming one side wall of the channel and a portion forming the bottom of the channel, the bottom portion being provided with an outwardly extending flange at its edge remote from the former flange spacing the bottom portion of the body away from the frame, the second mentioned flange having a passage therethrough the guide also comprising a strip forming the other wall of the channel and lapping the second mentioned flange, the strip having an angular arm extending through the passage under the bottom of the body whereby the strip and the arm form an angle lever fulcrumed near its angle, and means associated with the guide and coacting with said arm to move the lever on its fulcrum.

9. A window construction comprising a frame provided with a sash guide in the form of a channel for receiving the sash, the guide comprising a body having a flange forming one side wall of the channel and a portion forming the bottom of the channel, the bottom portion being provided with an outwardly extending flange at its edge remote from the former flange, spacing the bottom portion of the body away from the frame, the second mentioned flange having a passage therethrough, the guide also comprising a strip forming the other wall of the channel and lapping the second mentioned flange, the strip having an angular arm extending through the passage under the bottom of the body whereby the strip and the arm form an angle lever fulcrumed near its angle, and means associated with the guide

and coacting with said arm to move the lever on its fulcrum, said arm also having means for detachably interlocking with the second mentioned flange.

10. A window construction comprising a frame element and a sash element, one of said elements being provided with a channel for receiving the other element and consisting of a body having a portion forming one side wall of the channel and a portion forming the bottom of the channel, a strip forming the other side wall of the channel, the strip having an angular arm rigid therewith at one edge extending under the bottom of the channel and spring means associated with the element formed with the channel and acting on said arm to move the angle lever on its fulcrum and press said strip toward said other element.

11. A window construction comprising a frame provided with a sash guide in the form of a channel and consisting of a body having a portion forming one side wall of the channel and a portion forming the bottom of the channel, a strip forming the other side wall of the channel, the strip having an angular arm rigid therewith at its outer edge and extending at an angle to the strip and under the bottom portion of the body forming an angle lever fulcrumed near the outer edge of the strip and spring means associated with the guide and acting on said arm to move the angle lever on its fulcrum and press said strip against the sash, the arm also having means for detachably interlocking with the body.

12. A window construction comprising a frame provided with a sash guide in the form of a channel for receiving the sash, the guide comprising a body having a flange forming one side wall of the channel and a portion forming the bottom of the channel, the bottom portion being provided with an outwardly extending flange at its edge remote from the former flange, spacing the bottom portion of the body away from the former flange, the second flange having a passage therethrough, the guide also comprising a strip forming the other wall of the channel and lapping the second flange, the strip having an angular arm extending through the passage under the bottom of the body, whereby the strip and the arm form an angle lever fulcrumed near its angle, and spring means associated with the guide and coacting with said arm to move the lever on its fulcrum, the spring means and said arm having means for detachably interlocking.

13. A window construction comprising a frame provided with a sash guide in the form of a channel for receiving the sash, the guide comprising a body having a flange forming one side wall of the channel and a portion forming the bottom of the channel, the bottom portion being provided with an out-

wardly extending flange at its edge remote from the former flange spacing the bottom portion of the body away from the frame, the second mentioned flange having a passage therethrough, the guide also comprising a strip forming the other wall of the channel and lapping the second mentioned flange, the strip having an angular arm extending through the passage under the bottom of the body whereby the strip and the arm form an angle lever fulcrumed near its angle, and spring means associated with the guide and coacting with said arm to move the lever on its fulcrum, said arm also having means for detachably interlocking with the second mentioned flange and with the spring means.

14. A window construction comprising a frame provided with a sash guide having a channel for receiving the sash and comprising a body formed with a hollow stop portion forming one side wall of the channel, a strip forming the other side wall of the channel and having an angular arm rigid therewith at its outer edge and extending at an angle to the strip and crosswise of the guide into said hollow stop portion forming an angle lever fulcrumed near its angle at the outer edge of the strip and spring means located within the hollow stop portion and coacting with said arm.

15. A window construction comprising a frame provided with a sash guide having a channel for receiving the sash and comprising a body formed with a hollow stop portion forming one side wall of the channel, a strip forming the other side wall of the channel and having an angular arm rigid therewith at its outer edge and extending at an angle to the strip and crosswise of the guide into said hollow stop portion and forming an angle lever fulcrumed near its angle at the outer edge of the strip, and spring means located within the hollow stop portion and coacting with said arm, said arm having means for detachably interlocking with the spring means.

16. A window construction comprising a frame provided with a sash guide having a channel for receiving the sash and comprising a body formed with a hollow stop portion forming one side wall of the channel, a strip forming the other side wall of the channel and having an angular arm rigid therewith at its outer edge and extending at an angle to the strip and crosswise of the guide into said hollow stop portion and forming an angle lever fulcrumed near its angle at the outer edge of the strip, spring means located within the hollow stop portion and coacting with said arm, said arm having means for detachably interlocking with the spring means and also having means for detachably interlocking with the body.

17. In a window construction, the combi-

nation of a frame element and a sash element, one of said elements being provided with a channel for receiving the other element and comprising a body having a portion forming one side wall of the channel, a strip forming the other side wall of the channel and having an angular arm at its outer edge extending transversely of the channel and spring means associated with the element formed with the channel and acting on said arm, the spring means and the body having means for detachably interlocking with said arm, whereby the strip is removable.

In testimony whereof I have hereunto signed my name, at Syracuse, in the county of Onondaga and in the State of New York, this 22nd day of May, 1928.

ROY T. AXE.
